DESIGN FOR A BUCKLE

John J. Walsh, St. Louis, Mo., assignor to Alter-son Co., Inc., New York, N. Y., a corporation
of New York

Application May 14, 1936, Serial No. 62,625

Term of patent 3½ years

To all whom it may concern:

Be it known that I, John J. Walsh, a citizen of the United States of America, residing in the city of St. Louis and State of Missouri, have invented a new, original, and ornamental Design for a Buckle, of which the following is a specification, reference being had to the accompanying drawing, forming part thereof.

Figure 1 is a front view of a buckle showing my new design.

Figure 2 is a plan view of a buckle as shown in Figure 1.

I claim:

The ornamental design for a buckle substantially as shown.

JOHN J. WALSH.
